UNITED STATES PATENT OFFICE.

ELOF NORDSTROM, OF EAST ORANGE, NEW JERSEY, ASSIGNOR, BY MESNE ASSIGNMENTS, TO ALUMINUM SEAL CORPORATION, OF NEW YORK, N.Y., A CORPORATION OF NEW YORK.

ARTICLE-FEEDING MECHANISM.

Application filed October 25, 1924. Serial No. 745,862.

This invention relates more especially to that class of mechanisms in which articles are fed from bulk and arranged in a continuing series to be passed on to be operated upon by other machines or portions of the same machine.

The primary object of my invention is to provide an improved construction in mechanisms of this character which in the 10 preferred embodiment hereinafter shown, described and claimed, contemplates the feeding from bulk of articles having outwardly projecting portions of more or less irregular contour and the arrangement of 15 said articles in a predetermined order or presentation with respect to said projecting portions. The drawings show an adaptation of my invention to mechanism for feeding caps with lateral flanges or projections, 20 said caps being fed from bulk and subjected to a series of operations which arrange the caps in a continuing series with their crowns all presented in the same direction.

25 Specific objects of invention will appear in the specification and be pointed out in the claims, reference being had to the accompanying drawings exemplifying my invention and in which—

30 Figure 1 is a side elevation partly in section corresponding to the line 1—1 of Figure 2;

Figure 2 is a vertical section on the line 2—2, Figure 1;

35 Figure 3 is an enlarged fragmentary side elevation of the lower portion of the cap conveying chute and parts contiguous thereto;

Figure 4 is a transverse section on an enlarged scale corresponding to the line 4—4, 40 Figure 1;

Figure 5 is a similar enlarged section on the line 5—5, Figure 1;

Figure 6 is a side elevation similar to 45 Figure 3, showing certain of the parts in changed positions, parts being shown in section;

Figure 7 is a top plan view and section on an enlarged scale according to line 7—7, 50 Figure 6;

Figure 8 is a section and top plan view according to line 8—8, Figure 1;

Figure 9 is an end elevation of the compound slide removed;

Figure 10 is an end elevation of the guide 55 block or housing for said slide; and

Figure 11 is a side elevation similar to Figure 1, portions being broken away and parts shown in section.

Referring more particularly to the drawings, in the embodiment of my invention shown therein, the main frame of the machine comprises a base member 1, uprights 2, 2, and upper and lower side rails 3, 3. Midway of the length of upper side rail 65 3 is an elongated bearing 4 within which a shaft 5 is secured by means of a set screw 6. Journalled upon an overhanging portion of the shaft 5 is the hub 7 of a circular disk or plate 8 which is preferably 70 dished as indicated in Figure 2 and arranged opposite to the open end of a box or container 9 provided with an inclined bottom wall 10 and connected to the main frame by means of angle brackets 11, secured by bolts 12. Keyed to the reduced portion 13 of the hub 7 of said disk 8, is a spur gear 14 which as shown best in Figure 1 meshes with a spur sector 15. Said sector is oscillatably mounted upon a pin 16 80 carried by the main frame. Integral with the sector 15 is an arm 17 which is connected by a rod 18 with a spur gear 19. The spur gear 19 meshes with a smaller spur gear 20 keyed to a shaft 21, said shaft 85 being journalled in a bearing 22, which is integrally formed with one of the uprights 2 of the main frame. Keyed to the shaft 21 and arranged on the opposite side of the bearing 22 from said gear 20, is a pulley 23 which may be driven by a suitable belt (not shown). Axially spaced from the disk or dished plate 8, is an annulus 24 which together with a corresponding portion of said dished plate, forms a peripheral 90 slot 25. A frusto-conical flange 26 which is integrally formed with the annulus 24 extends outwardly to the adjacent circular edge of the bottom wall 10 with which it forms a substantially continuous bottom wall for the hopper. Said disk 8 and annulus 24 are connected by a strap 27 and bolts 28 and provided with enlarged peripheral faces in which are formed peripheral grooves 29, 29. Running in said grooves 105 are three pairs of axially spaced rollers 30 which rotatably support the disk 8 and annulus 24. The rollers 30 are journalled up-

on pins 30' carried by circular plates 34', 34' which are rigidly mounted on the main frame in the manner to be presently described.

5 The base member 1 of the main frame, according to the present embodiment of my invention carries a pair of longitudinally extending blocks or guides 31, 31. These guides are provided with longitudinal 10 grooves 32, 32. Mounted upon the blocks 31, 31, are the base flanges 33, 33, of the upwardly extending chute sections 34, 34. The rings or circular plates 34', 34', are provided below with integrally formed rectangular 15 portions 34^a, 34^a, which rest upon the upper edges of the chute column sections 34, 34, as shown in Figures 2 and 11. Suitable bolts 34^b which pass thru the oppositely disposed parts 34, 34, and 34^a, 34^a, are secured 20 in a block or plate 34^c (see Figure 2). As shown best in Figures 1 and 4, a pair of oppositely disposed track bars 35, 36, are arranged between the chute members 34, 34, the track bar 36 being extended upwardly 25 toward the right to form a tangential portion 36^a and circular portion 36^b which terminates at 37. As shown at the top of Figure 2, the circular extension 36^b of the track bar 36 is rigidly clamped between oppositely arranged circular plates 34', 34', 30 which substantially conform thereto. Said circular portion 36^b forms almost a complete circle having a considerably larger diameter than the inner corner 26^a (see Fig. 35 2) of the flange 26 of annulus 24. The track bar 35 on the other hand terminates above in an overhanging point or spur 35^a. Said track bars 35 and 36 in the present embodiment of my invention, are spaced apart 40 for a suitable distance to slidably engage the outer circular wall of the crown portion of a bottle sealing cap C. In effect, the track bars 35, 36, form channels 34^a, 34^a, on opposite sides of the track bars 35, 36, said channels terminating below in the divergent passages 38, 38, formed by the wedge shaped partition 39. Interposed between the guide blocks 31, 31, is a partition 40 which forms the parallelly disposed channels 41, 41, extending longitudinally of said guide blocks and at their forward ends opening into cap turning chambers 42 and 43.

As shown best in Figures 7 and 8 the cap turning chambers 42 and 43 merge into a 55 forwardly contracted passageway 44 leading to a channel 45 thru which all caps are passed after they have been arranged in a given order with respect to their contour.

60 Referring now to Figures 1, 2, 3, 5 and 6 and 11, the gear wheel 20 carries a pin 46 upon which is journaled one end of a connecting rod 47, the other end of said connecting rod being pivotally connected by a pin 48 to an arm 49 which oscillates about a 65 pin 50 on the main frame. A laterally pro-

jecting pin 51 carried by the arm 49 reciprocates in a groove 52 formed in one end of a link or rod 53 and thus provides a lost motion connection between the swinging arm 49 and a cap releasing slide to be presently referred to. The forward end of said rod 53 is pivotally connected by a pin 54 with a reciprocable slide 55 which as shown in Figure 5 is slidably supported in a slotted block 56 mounted on the outer wall of chute 70 34. Rigidly mounted upon the slide 55 by means of screws 57, 57, and spaced therefrom by blocks 58, 58, are stop fingers 59 and 60, the latter being arranged at a lower level than the former as shown in Figure 75 6. It will appear from Figures 3 and 6, that as the slide 55 is reciprocated to and fro, the upper finger 59 is moved into position to support a column of caps C above at the same time that the lower finger is 80 moved out of the path of a lower cap which is thus released and separated from the column as indicated in these figures. As shown in Figures 1 and 8, the lower end of swinging arm 49 is movably connected by the parallel links 61, to a cross-head or block 62 thru which extends a pin 63 to which the links are pivotally connected. Projecting forwardly from the cross-head block 62 is a 85 pair of bottom plates or slides 64 which are recessed or cut away at 65 (see dotted lines in Figures 7 and 8) to conform to the inclined abutments 66, 66, formed on the oppositely disposed blocks or pads 67, 67. At the same time, the overhanging forward ends of the slides 64, 64, slide over the upper surfaces of the blocks 67, 67. Reciprocably mounted within the parallel channels 41, 41, are laterally spaced slides 68, 68, which project forwardly from the cross-head block 90 62. The forward ends of said slides are adapted to engage the crowns of caps to be moved and for this purpose are provided with rectangular recesses 69, 69, which accommodate laterally projecting portions of a cap such as the flanged edge or lugs. It will be noted further that each of the bottom slides 64, 64, is provided with a groove 64^a 95 extending along the inner upper edge thereof, said groove being spaced from the central partition 40 at a suitable distance to receive the outwardly flanged edge of the cap. It will be understood from this description that as the cap drops upon the bottom slide 64, its flanged edge rests in the groove 64^a 100 while the crown of said cap slides along the central wall or partition 40. It results from this relation that as the cap is brought into engagement with one or the other of the inclined cam walls 70^a, it is swung about that edge of its flange which rests in the groove 64^a and is thus turned over into the position shown at the right of Figure 7. According to the present embodiment of my invention, the cam walls 70^a are formed by 105 110 115 120 125 130

inclined faces of cam blocks 70 which are rigid with the central partition 40 and constitute means for imparting a 90° turn to the caps which are thus brought into a similar

5 order of presentation before the caps on opposite sides of the central partition are combined into a single series by way of the passage-way 44 and channel 45.

10 The operation of my improved article-feeding mechanism will now be readily understood. The articles dumped in bulk into the receptacle or box 9 are moved toward the movable end of the hopper comprising the oscillatory disk 8 and frusto-conical flange 26. The resulting tumbling of the caps causes them, according to the present embodiment of my invention, to assume one of two opposite positions as they settle into the peripheral slot which is formed between the annulus 24 and the oppositely disposed surface of the disk 8. From an inspection of Figure 1 in connection with Figure 4, it will be understood that the caps enter between the track bars 35 and 36 15 mainly when they are propelled by a clockwise movement of the oscillatory head of the hopper and with the flanged edges and finger lugs arranged in one or the other of the vertical channels 34^a, 34^b, into which the chute is divided by said track bars. As the caps C move downwardly, thru the chute 34 with the outer walls of their crown portions slidably engaging the track bars 35, 36, they form in a column above one or 20 the other of stop fingers 59, 60, as shown in Figure 6 in which the arrangement of the parts corresponds with the positions shown in Figure 1. As the swinging arm is thrown toward the right, the upper slides 68, 68, are propelled in the same direction until one of said slides engages a separated cap in one or the other of said channels 41, 41, in the guide blocks 31, 31. At about this 25 time, the pin 51 has completed its lost motion travel in slot 52 and has begun to throw the slide 55 toward the right. During this movement, the cap at the bottom of the chute 34 which has been previously separated from the column above, is moved toward the right and turned over into the position of the cap shown at the right in Figure 6. At the same time, the stop finger 60 releases another cap from the column while the stop finger 59 moves into position 30 to support the column above. Referring now to Figure 7, it will be seen that caps C are turned in one or the other direction to lie flatwise on the floor of chambers 42, 43, according to which direction their flanged edges and finger lugs are presented away from the central partition 40. At each forward movement of the bottom slides 64, 64, said caps are propelled thru the passage-way 44 into the common channel

45 in which they are arranged in a continuous series with their crown presented in the same direction. 65

I claim—

1. In a cap-feeding machine, the combination with a hopper, of a chute connected thereto, said chute being provided with spaced track bars adapted to engage the outer walls of caps arranged in either of two opposite presentations, means movable across the outlet end of said chute for receiving and arranging said caps according to their presentation, and means cooperating with said cap-receiving and arranging means for rearranging the caps of both presentations into a single series of like presentation. 70 75 80

2. In a machine of the character described, the combination with a hopper provided with a dished circular plate movable about a horizontal axis and an annular plate 85 axially-spaced from said plate but movable therewith, said annular plate being provided along its inner edge with a latterly-presented circular flange, of a chute disposed to receive articles from the peripheral opening formed between said circular and annular plates, and a track-bar in said chute, said track-bar being provided with an upwardly-extending portion arranged between said circular and annular plates whereby 90 95 said hopper is adapted to deliver articles to said chute in either of two opposite presentations.

3. In a machine of the character described, the combination with a hopper provided with an inclined bottom wall and an oscillatory end wall, of a circular flange spaced from said end wall and oscillatable therewith a chute for conveying articles from said hopper, oppositely disposed track 100 bars within said chute, one of said track bars having an extension extending between said end wall and circular flange and conforming to the latter, and means for conveying articles from said chute. 105 110

4. In a cap-feeding machine, a cap-feeding head movable about an axis and provided with a downwardly presented discharge slot, a chute extending away from said cap-feeding head, a fixed track in said chute including a portion extending upwardly between the walls of said slot, and means receiving caps from said chute and arranging them in a predetermined order of presentation. 115 120

5. In a cap-feeding machine, a cap-feeding head movable about an axis and provided with a downwardly presented discharge slot, a chute extending away from said cap-feeding head, a fixed track in said chute including a portion extending upwardly between the walls of said slot, a slide traversing said chute for conveying caps there- 125

from, and means cooperating with said slide for arranging the caps in a predetermined presentation.

6. In a cap-feeding machine, a cap-feeding head movable to and fro and provided with a downwardly presented discharge slot, a chute for conveying caps away from said cap-feeding head, a fixed track in said chute projecting into said slot, said track being adapted to intercept and deflect caps into said chute, and means receiving caps from said chute and arranging them in a predetermined order of presentation.

7. In a cap-feeding machine, an oscillatable cap-feeding head provided with a discharge slot, a chute suitably formed to receive caps when presented in either of two different ways, a fixed track in said chute and extending between the walls of said slot, said track being provided with means adapted to deflect caps into said chute when presented in either of said ways, and means receiving said caps from said chute and arranging them in a single series of similarly presented caps.

8. In a cap-feeding machine, the combination with a hopper, of a chute adapted to receive flanged caps in either of two opposite presentations, laterally-spaced walls forming cap-conveying channels adapted to receive said caps edgewise, oppositely presented cam walls for turning oppositely-presented caps in opposite directions, and slides mounted in said channels for controlling the admission of caps thereto and propelling said caps against said cam walls for turning them into similarly presented order.

9. In a machine of the character described, the combination with a base provided with channels for receiving caps edgewise in one or the other of two opposite presentations, of a chute having branches leading respectively to said channels, slides for controlling the admission of caps to said channels, and means arranged along said channels for turning said caps to arrange them in substantially similar order under the propulsion of said slides.

10. In a cap-feeding machine, an oscillatable cap-feeding head comprising a circular plate and an annulus spaced therefrom to form a peripheral slot, a chute provided with a slot communicating with said peripheral slot, the slot in said chute being provided with diverging branches, a fixed track in said chute having one end thereof extending along and between the walls of said slot and terminating at its other end adjacent the point at which said branches of the chute diverge, and means receiving caps from said divergent branches of the chute and arranging them in one and the same predetermined order of presentation.

11. In a cap-feeding machine, an oscillatable cap-feeding head comprising a sub-

stantially upright circular plate and an annulus spaced therefrom to form a peripheral slot, a chute extending downwardly from said oscillatable head, oppositely arranged track bars in said chute for slidably engaging the crown portions of caps having laterally projecting flanges, said track bars adapting said chute to convey caps from said oscillatable head in either of two oppositely presented arrangements, means for separating the caps having one presentation from those having the other presentations, and means for arranging all of said caps in the same order of presentation.

12. In a machine of the character described, the combination with a hopper provided with an oscillatory end wall and a circular flange spaced from said end wall and oscillatable therewith, of a chute for conveying articles from said hopper, a track-bar within said chute and having an extension arranged between said end wall and circular flange, said extension conforming to the latter, and means for conveying articles from said chute.

13. In a machine of the character described, the combination with a hopper comprising an oscillatory end wall, a circular plate spaced axially from said end wall and oscillatable therewith, said circular plate being provided with a laterally presented frusto-conical flange, and a container having a bottom wall conforming to said frusto-conical flange, a chute for conveying articles from the said hopper, and a track-bar within said chute, said track-bar having an extension arranged between said end wall and circular flange for engaging articles in either of two oppositely presented arrangements.

14. In a cap-feeding machine, a cap-feeding head movable about an axis and provided with a downwardly presented discharge slot, a chute extending away from said cap-feeding head, annular plates arranged above and rigidly connected to said chute, a fixed track in said chute, said track having an upwardly-extending portion clamped between said annular plates, and means receiving caps from said chute.

15. In a cap-feeding machine, a cap-feeding head movable about an axis and provided with a downwardly presented discharge slot, a fixed chute extending downwardly from said cap-feeding head, a fixed track in said chute, said track having an upwardly extending portion arranged between the walls of said slot, the outer peripheral edge of said upwardly-extending portion projecting outwardly beyond the periphery of said cap-feeding head, and annular plates extending around the periphery of said cap-feeding head, the upwardly extending portion of said track being clamped between said annular plates.

16. In a cap-feeding machine, an oscillat-

able cap-feeding head comprising a circular plate and an annulus spaced therefrom to form a peripheral slot, said cap-feeding head being provided with an outwardly-presented peripheral groove, a chute communicating with said peripheral slot, a circular frame arranged above said chute and extending around the periphery of said cap-feeding head, and rollers journaled in said 10 circular frame and running in said peripheral groove for rotatably supporting said cap-feeding head.

17. In a cap-feeding machine an oscillatable cap-feeding head comprising a substantially upright circular plate and an annulus spaced therefrom to form a peripheral slot, a chute extending downwardly from said oscillatable head, oppositely arranged track-bars in said chute for slidably 15 engaging the crown portions of caps having laterally projecting flanges, one of said track-bars having an upwardly-extending portion arranged within said peripheral slot, the outer edge of said portion projecting outwardly beyond the outer periphery of 20 said cap-feeding head, the other of said track-bars terminating in a spur presented along and spaced inwardly from the inner edge of the first-mentioned track-bar, annular plates extending around the periphery 25 of said cap-feeding head, said upwardly extending portion of the first-mentioned track-bar being clamped between said annular plates, and means carried by said annular plates for supportably engaging the periphery of 30 said cap-feeding head.

ELOF NORDSTROM.
